RIBBON FEED DEVICE

Leonhard F. Reinhold, Great Kills, N. Y., assignor
to Radio Corporation of America, a corporation
of Delaware

Application May 31, 1946, Serial No. 673,546

7 Claims. (Cl. 197—162)

1

This invention relates to typewriter ribbon feed devices and, more particularly, to an arrangement for controlling a typewriter ribbon such as called for in the operation of telegraph typewriters and typewriting machines which comprise a type wheel.

It is an object of my invention to provide an improved ribbon feed mechanism for a telegraph typewriter such that the ribbon spools when requiring reversal of their motions will be reversed in operation by means of a simple mechanism that is also readily actuated from a rotating cam.

It is another object of my invention to provide a transfer mechanism operable, whenever either of the ribbon spools becomes unwound, to engage a driving pawl with an associated ratchet wheel for causing that particular spool to start re-winding the ribbon.

My invention will now be described in more detail, reference being made to the accompanying drawing, the sole figure of which represents diagrammatically a combination of mechanical elements which are essential to the carrying out of the invention.

Referring to the drawing, I show therein two shafts 1 which respectively carry the ribbon spools 1a and 1b, and ratchet wheels by which either one of the spools is driven to wind up the ribbon, the other spool being free to pay out the ribbon. The ratchet wheels are driven by a pawl member 21 which is arranged to have a toggle action so that it bears against either one or the other of the two ratchet wheels. The pawl member 21 is a portion of a toggle-acting member 10 which is swiveled on a pivot pin 13 carried by a draw-bar 9. The draw-bar is held in position at its upper end by a stationary pin 17 extending through a slot 17a in the draw-bar. At the lower end of the draw-bar 9 is a pivot pin 7 by which linkage is effected with an operating lever 5.

Lever 5 is pivoted at 6 and the left hand end is provided with a roller 5a which bears against the periphery of a cam 8a. This cam is driven counter-clockwise on a shaft 8, single revolutions being made in a start-stop manner after each operation of a printing platen 29. The ink ribbon 24 and record tape 28 are both fed between the platen 29 and a typewheel 25a.

The typewheel rotates on a shaft 25, the indexing motion of which it is unnecessary to describe since it forms no part of the instant invention.

The ink ribbon 24 is wound on spools 1a and 1b and is guided by guide rollers 19 in front of the typewheel 25a. The record tape 28 is trained

2

over two rollers 26 and 30, and is guided by members 27 between the ink ribbon and the printing platen 29.

Obviously, the striking of the printing platen 29 against the record tape exerts pressure between this platen and the typewheel, and an ink impression of the opposed type character is thus formed on the record tape.

The draw-bar 9 is pulled upwardly by tension 10 of a spring 18. This tension also tends to engage the roller 5a on the lever arm 5 against the periphery of the cam 8a. When the hump of the cam raises the roller 5a the consequent rocking action of the lever 5 draws the pawl 21 downwardly and turns the ratchet wheel through an arc of one tooth space. Then the ratchet wheel is retained by a retaining pawl member 14 which is pivoted at 16 and held against the ratchet wheel by means of a spring 14a.

When the ratchet wheel 1a is being driven in the manner above described, the ratchet wheel 1b is free to permit unwinding of the ink ribbon because its associated retaining pawl 14 is held out of engagement. Each of the pawls 14 is provided with a pin 15 resting upon the edge of an upwardly extending arm 22 that is formed integrally with the member 10. A spring 23 is anchored at its two ends by pins 11 and 12, pin 11 being mounted on the driving pawl 21 and pin 12 being mounted on the draw-bar 9. Since the two pins 11 and 12 are on opposite sides of the pivot pin 13 the spring 23 operates to hold the pawl member 21 either on one side or the other until its position is reversed by the action of one or the other of two lever members 2a and 2b.

The two bellcrank levers 2a and 2b are mounted respectively on one and the other of two pivot pins 3 and are normally held by springs 20 so as to exert a slight pressure of their rollers 4a and 4b against the ribbon for maintaining the ribbon taut. When, however, the ribbon is completely unwound from one of the spools it tends to rotate the lever members 2a and 2b in such a manner as to exert pressure on the nearer one of the two side arms of the member 10. This action causes the lever 10 to swing to the other side where the pins 15 on the retaining pawls 14 are moved into a new position and the retaining pawl which was previously relieved from duty is now engaged with its ratchet wheel, while the previously engaged pawl is drawn away from its ratchet wheel. In this manner the next operation of the driving pawl 21 is such as to produce a reverse action on the winding of the ink ribbon.

A feature of the design that is worthy of note

is the fact that when the toggle member 10 is in the position shown in the drawing the outer edge of the right-hand arm 22 lies parallel to the direction of motion of the draw-bar 9. Hence the downward movement of the draw-bar and toggle member has no effect upon the position of clearance between the right-hand retaining pawl and the ratchet wheel 1b. On the left side of the toggle member the inclination of the outer edge of the arm 22 with respect to the axis of the draw-bar 9 is such that a space between it and the pin 15 (to the left) is opened up and the retaining pawl 14 cannot be lifted out of engagement with its associated ratchet wheel 1a until after the next ribbon feed reversal takes place in accompaniment with the toggle action of member 10. Of course, when the toggle member leans the other way from that shown in the drawing then the left hand and right hand conditions set forth in this paragraph are reversed.

Another feature of the invention relates to the unequal angles made by the directions of travel of the ribbon 24 as it passes over the rollers 4a and 4b, respectively, at the time of performing the automatic reversing function. When the spool 1a is fully wound the angle at roller 4a is considerable, whereas the angle at roller 4b is very slight due to the fact that spool 1b is completely unwound. The anchorage of the ribbon ends on the two spools makes the ribbon taut when one of the spools becomes completely unwound. The greater angle of deflection at roller 4a enables the ribbon to exert a considerable pressure thereon so as to rotate the lever 2a clockwise for actuating the toggle member 10. On the right hand side, however, the angle of deflection of the ribbon at roller 4b is so slight (due to the tension of spring 20) that substantially no movement of the lever takes place.

Still another feature of the invention resides in its freedom from adverse influences in case of shock. It is contemplated that the type-writing machine with which my ribbon feed and ribbon reversing device may be associated might be carried aboard an airplane or other moving vehicle. In case of sudden shock to which the apparatus may be subjected it is conceivable that a sudden change in the direction of motion of the vehicle might cause the toggle member 10 to be thrown from one side to the other. The only result of this action would be to reverse the direction of ribbon feed before one of the spools had become completely unwound. Obviously, in this case the retaining pawls 14 would assume their appropriate positions for maintaining the direction of ribbon feed as then in effect and until the next normally produced reversing operation took place.

It will be understood by those skilled in the art that various modifications of my invention may be made without departing from its spirit and scope.

I claim:

1. A typewriter ribbon feed device having two winding spools for the ribbon, ratchet wheels coaxially mounted with respect to said spools, a spring tensioned toggle member, an integral portion of which is constituted as two engaging pawls, each one of which is engageable with one of said ratchet wheels at a time, two retaining pawls each alternately engageable with a respective ratchet wheel, means including a cam-operated lever system for producing tangential motion of one of the engaging pawls with respect

to the ratchet wheel with which it is engaged, thereby to cause a winding up of the ribbon on the spool associated with that ratchet wheel, and ribbon-controlled mechanism for releasing the retaining pawl from engagement with the other ratchet wheel to permit the other ratchet wheel to pay out the ribbon and for causing said toggle member to shift the other of said engaging pawls to the other ratchet wheel in response to an increase in ribbon tension.

2. A typewriter ribbon feed device having two winding spools for the ribbon, ratchet wheels coaxially mounted with respect to said spools a retaining pawl for each ratchet wheel, a spring tensioned toggle member having an integral portion thereof constituted as a two-pronged engaging pawl, a draw-bar providing support for said toggle member and movable longitudinally along an axis which bisects and is perpendicular to a line of interconnection between the axes of said spools, a stationary pin extending through a slot in said draw-bar for positioning the upper end thereof, a spring for retracting said draw-bar upwardly, a cam-controlled lever for positioning said draw-bar at its lower end and for actuating the same, and a ribbon controlled mechanism including a roller which is in contact with the ribbon for causing said toggle member to shift its pawl from one to the other of its alternate positions of engagement with the respective ratchet wheels.

3. A typewriter ribbon feed device having two winding spools for the ribbon, ratchet wheels coaxially mounted with respect to said spools, a retaining pawl for each ratchet wheel, a spring tensioned toggle member having an integral portion thereof constituted as a two-pronged engaging pawl, a draw-bar providing support for said toggle member and movable longitudinally along an axis which bisects and is perpendicular to a line of inter-connection between the axes of said spools, a stationary pin extending through a slot in said draw-bar for positioning the upper end thereof, a spring for retracting said draw-bar upwardly, a cam-controlled lever for positioning said draw-bar at its lower end and for actuating the same, and means including a ribbon controlled mechanism for causing said toggle member to alternately shift its pawl including two bell-crank levers adapted and arranged to be selectively actuated by the ribbon in dependence upon the relative angles of deflection of said ribbon at points of contact thereof with one and the other respectively of two rollers each mounted on a respective bell-crank lever.

4. In a typewriter ribbon feed mechanism, two ribbon spools and associated ratchet wheels, a two-pronged driving pawl alternatively engageable with one and the other of said ratchet wheels, said pawl being constituted as an extension from a toggle-acting member, tensional means for tilting said member to one side or the other, thereby to engage its pawl with a given ratchet wheel, cam-controlled means for reciprocating said pawl tangentially with respect to the ratchet wheel with which it is engaged, a pivoted retaining pawl for each ratchet wheel, and means operable by said toggle-acting member for holding an appropriate one of said retaining pawls in a position of disengagement from its ratchet wheel for permitting pay-out of ribbon from the associated spool.

5. The device according to claim 4 and including an automatic feed reversing device operable in response to an increase in ribbon tension be-

tween its two spools for controlling said toggle-acting member thereby to shift the engagement of said driving pawl from one to the other ratchet wheel.

6. In a device for reversing the direction of feed of a typewriter ribbon, two spools having ribbon anchoring means at their cores, a ratchet wheel for each spool, reciprocating means including a spring tensioned toggle member forming a two-pronged driving pawl for selectively engaging with a single one of said ratchet wheels to turn the same with its spool and thus to wind up the ribbon, two bell crank levers each of which carries a roller for engagement with said ribbon, other rollers mounted on stationary pivots and serving to guide said ribbon in directions such that the ribbon is variably deflected by said lever-carried rollers, and means mechanically linking an appropriate one of the bell crank levers to said driving pawl and operable to shift said pawl from one to the other of its ratchet wheel engaging positions, the greater deflection of the ribbon on the side of the full wound spool being determinative of a relatively greater vector value of force applied to the bell crank lever on the operating side due to tightening of the ribbon when its spool on the other side becomes fully unwound.

7. A typewriter ribbon feed mechanism comprising two ribbon spools with associated ratchet wheels attached thereto, a pivoted spring tensioned toggle member having engaging pawls to bear against either one or the other of said ratchet wheels, said pivoted spring tensioned toggle member also having upwardly extending arms

associated therewith, a draw bar having supporting means for said pivoted spring tensioned toggle member, two retaining pawls each positioned between one of said ratchet wheels and one of the extending arms of said toggle member, a spring for retracting said draw bar upwardly, a cam control lever linked to said draw bar at its lower end for actuating the same, and means including a ribbon controlled mechanism with two pivoted rollers, each roller being in contact with the ribbon, for causing said toggle member to shift the engaging and retaining pawls from one to the other of their alternative positions of engagement with the respective ratchet wheels.
